UNITED STATES PATENT OFFICE.

JOHN LOUIS BARRETT, OF CHICAGO, ILLINOIS.

STEAM-ECONOMIZER.

1,387,227.

Specification of Letters Patent.

Patented Aug. 9, 1921.

Application filed February 28, 1920. Serial No. 362,062.

To all whom it may concern:

Be it known that I, JOHN LOUIS BARRETT, a citizen of the United States, and a resident of Chicago, in the county of Cook and State 5 of Illinois, have invented certain new and useful Improvements in Steam-Economizers, of which the following is a specification.

My invention is an improvement in steam economizers, and has for its object to provide a device of the character specified, adapted for use with steam engines and to be arranged between the boiler and the engine for conserving the exhaust from the engine and returning it to the boiler for re- 15 use before the exhaust has lost its heat.

In the drawings:

Figure 1 is a top plan view of the improvement with parts in section,

Fig. 2 is a side view,

Figs. 3 and 4 are sections on the lines 20 3—3 and 4—4 respectively of Fig. 1, the latter figure looking in the direction of the arrows adjacent to the line.

Fig. 5 is a section on the line 5—5 of Fig. 25 6, looking in the direction of the arrow adjacent to the line,

Fig. 6 is a section on the line 6—6 of Fig. 5, looking in the direction of the arrow adjacent to the line,

Fig. 7 is a view similar to Fig. 5, showing 30 a modified construction of yieldable connection.

The present application covers the same subject matter as my prior application Serial 35 No. 844,014, filed June 9, 1914, allowed July 10, 1917, and which became forfeited Jan. 10, 1918.

The present embodiment of the invention 40 is designed to be arranged between a steam engine and the boiler, the steam passing from the boiler to the engine to drive the same, and the economizer receives the exhaust products from the engine and returns them to the boiler in a heated condition.

45 The improvement is supported by a base 1 of suitable construction, having supporting legs 2, and the improvement comprises a pair of cylinders 3 and 3^a, arranged at opposite sides of the base, and a valve chamber 4 is arranged between the cylinders. Each cylinder is provided with a column 5, secured to the base, and the valve chamber is provided with a similar column 6, also secured to the base.

55 Pistons 7 and 7^a are arranged in the respective cylinders 3 and 3^a, and piston rods 8

and 8^a are connected with the respective pistons. Each piston rod passes through a stuffing box 9 in one head of the cylinder, and the rods are connected with cross heads 10, each of which is movable in guides 11. An operating shaft 12 is journaled in bearing brackets 13 on the base and transversely thereof, and a disk 14 is secured to each end of the shaft, each disk being connected to 60 the adjacent cross head 10 by means of a link 15. The links 15 are pivoted at one end to the cross heads, and at the other end to an eccentric wrist pin 16 on the adjacent disk. 70

A driving shaft 17 is journaled in bearing brackets 18 on the base and parallel to the operating shaft 12, and a pulley 19 is secured to the shaft near one end thereof. A belt 20 connects the pulley with a rotating element of the engine, and a pinion 21 is keyed to the driving shaft near the opposite end from the pulley and meshes with a gear wheel 22, journaled loosely on the shaft 12. 75

It will be obvious that when the driven shaft is in operation, the gear wheel 22 will be driven continuously and mechanism is provided, arranged between the gear wheel and the operating shaft 12, for moving the same. Each cylinder 3 and 3^a is provided 80 with inlet ports 23 and 23^a at its opposite ends, and pipes 24 and 24^a connect the respective ports with the opposite ends of the valve chamber 4.

The exhaust pipe 25 from the engine extends transversely of the cylinders 3 and 3^a at the end remote from the operating shaft 12, and pipes 26 and 26^a lead from the exhaust pipe to the pipes 24 and 24^a. Each of the pipes 26 is connected to the adjacent pipe 95 24 intermediate the ends of the said pipe, and each of the pipes 26^a is connected to the adjacent pipe 24^a intermediate the ends of the said pipe. The pipes 24 open into the front end of the valve chamber at opposite sides 100 thereof, and the pipes 24^a open into the valve chamber at the other end and at the opposite sides thereof.

Valves 27 and 27^a are slidably mounted in the valve chamber at opposite sides thereof, the said valves being arranged to alternately close the inlet ends of the pipes 24 and 24^a at the adjacent side, and valve stems or rods 28 and 28^a are connected with the respective valves, each stem or rod extending 105 through a stuffing box 29 in the end of the valve chamber. 110

A pipe 30 leads from the top of the valve chamber to the boiler, opening in the said boiler at any suitable point, and check valves 31 are arranged in the pipes 26 and 26^a as indicated in dotted lines in Fig. 2, each check valve being so arranged that while the exhaust may pass freely from the exhaust pipe 25 to the respective pipes 24 and 24^a, it cannot return, the valves closing to prevent such return.

The valve stems or rods 28—28^a pass through sectional guide brackets 32 extending upward from the base, and a roller 33 is journaled on the opposite end of each stem or rod from the valve. Each of the rollers engages a cam groove 34 in the inner face of a cam wheel 35 or 35^a, keyed to the operating shaft 12, and it will be noted that each cam groove consists of two portions concentric with the shaft but of unequal radius.

The connection between the concentric portions of each groove is sharp in pitch, so that the movement of the roller from one concentric portion to the other is quick. When the roller passes from the portion of less radius to the portion of greater radius, the valve connected with the roller is moved longitudinally of the valve chamber, opening the inlet end of the pipe 24 and closing the inlet end of the pipe 24^a.

Each of the cam wheels 35 and 35^a is keyed to the shaft indicated at 36, and in addition, a set screw 37 is threaded through an opening in the hub of the wheel to rigidly secure the wheel to the shaft. A disk 38 is journaled loosely on the shaft adjacent to the gear wheel 22, and the disk and the gear wheel are rigidly connected in spaced parallel relation by means of rivets 39 or the like, each rivet being encircled between the disk and the gear wheel by a sleeve or arbor 40.

The disk and the gear wheels are arranged between the wheels 35 and 35^a, and the said disk and gear wheels are spaced apart from each other to permit the connection of a radial arm 41, with the shaft between the disk and the gear wheel. The arm 41 has a hub 42 which encircles the shaft, and a key 43 is provided for rigidly connecting the arm with the shaft.

Levers 44 and 44^a are arranged on opposite sides of the shaft 12, each lever having a transverse bearing 45 intermediate its ends, and nearer the lower end than the upper, and the bearings engage stub shafts 46, arranged between the disk and the gear wheel and supported at their ends by the said disk and gear wheel.

Other levers 47 and 48 are arranged between the disk and the gear wheel, each of the said levers having a bearing 49, intermediate its ends, for engaging the stub shaft 50, the said stub shafts being supported in the same manner as the shafts 46 and parallel there-

with. The lever 47 is arranged outside of the lever 44, while the lever 48 is arranged outside of the lever 44^a. Each of the levers 44 and 44^a is connected at its lower end to the adjacent lever 47 or 48 as the case may be, by means of a pair of links 51.

A pair of links 52 connect the upper end of the lever 47 with the outer end of the radial arm 41, and an eye-bolt 53 is pivoted to the upper end of the lever 48 as indicated at 54. The other end of the eye bolt passes through a frusto-conical opening 55 in a lug 56, connecting the disk and the gear wheel, and a wing nut 57 engages the threaded portion of the bolt on the opposite side of the lug from the lever.

A coil spring 58 connects the upper ends of the levers 44 and 44^a. It will be noted from an inspection of Fig. 5, that the radial arm 41 normally stands parallel with the lever 44 and 44^a and at equal distances from the said levers, and the spring 58 holds the parts in the position of Fig. 1, that is, with the levers 44—44^a—47— and 48 approximately parallel.

The operation of the device is as follows: With the engine running, the shaft 17 is rotated continuously and the gear wheel 22 being connected to the shaft by means of the pinion 21, is also rotated continuously, and since the disk 38 is rigidly connected therewith, the frame constituted by the gear wheel and the disk 38 will rotate with the shaft 17. Since the levers 44—47—44^a and 48 are carried by this frame, they will rotate with the frame, and the arm 41 will be carried with the frame, thus rotating the shaft 12.

There is a drag on the arm 41 as the frame above mentioned rotates, which tends to carry the arm with the frame. Should the frame advance or move angularly with respect to the shaft, the upper end of the levers 47 will move laterally to the right of Fig. 5. This movement of the lever 47 tends to swing the upper end of the lever also to the right, putting the spring 58 under tension.

The tension of the spring is regulated by means of the wing nut 57 to a degree such that when the device is in operation, the parts will occupy the position shown in Fig. 5, that is, with the arm 41 parallel with the shafts 47—44—44^a— and 48. As the shaft 12 rotates, the disks 14 are rotated, and the pistons 7 and 7^a reciprocate longitudinally of the cylinder.

When the piston 7 moves in the direction of the arrows shown in Fig. 1, the exhaust products from the pipe 25 are drawn through the pipe 26^a and the pipe 24^a and the port 23^a into the end of the cylinder remote from the shaft 12. The exhaust steam already in the other end of the cylinder is driven out by way of the port 23, and the pipe 24 to the

valve chest, the valve 27 being at this movement at the end of the chamber remote from the shaft 12, that is, in a position to uncover the inlet end of the pipe 24 and to cover the inlet end of the pipe 24^a.

The pistons 7 and 7^a are set 90° apart, that is, the wrist pin 16 of the piston 7^a is 90° in advance of the wrist pin of the piston 7. The rollers 33 of the valve 27 and 27^a are 10 similarly arranged. The arrangement is such that when the piston 7 moves toward the shaft 12 the inlet end at the valve chest of the pipe 24 will be open and the inlet end of the pipe 24^a will be closed. At the opposite side, that is, adjacent to the cylinder 3^a 15 the valve 27^a is closing the inlet end of the pipe 24 and is leaving the inner end of the pipe 24^a open.

In this manner the exhaust products will 20 be passed from the pipe 25 through the cylinders 3 and 3^a to the valve chest or chamber 4 and from thence by way of the pipes 30 to the boiler.

In Fig. 7 is shown a modified arrangement of counterbalancing mechanism. In 25 this arrangement, the disk 38^a is keyed to the shaft 12^a by means of a key 43^a and the arm 41^a is connected to the upper end of a lever 59, by means of a pair of links 60. 30 The lever 59 has a bearing 60 intermediate its ends, engaging a shaft 50^a connecting the disk 38^a with the gear wheel 22.

Another lever 61 is arranged at the opposite side of the shaft 12^a, the lever having a 35 bearing 62 intermediate its ends engaging another shaft 50^a connecting the gear wheel and the disk. The lower end of the shaft 59 is provided with a cup extension 63, and a somewhat similar extension 64 is connected 40 to the lower end of the shaft 61 in a manner to be described. A coil spring 65 is arranged between the extensions 63 and 64, one end of the spring seating in the extension 63 and the other in the extension 64.

45 The extension 64 is provided with a central internally threaded nipple 66, and a threaded stem 67 engages the nipple. The outer end of the stem is forked and the arms 68 of the fork fit on opposite sides of the 50 lower end of the lever 61, and are pivoted

thereto. An eye bolt 69 is pivoted to the upper end of the lever 61, and the bolt passes through a lug 55^a connecting the disk and the gear wheel, and is engaged by a wing nut 57^a on the opposite sides of the lug from 55 the lever.

The disk 38^a is connected to the gear wheel behind rivets 39 in the same manner as the disk 38 is connected. In the operation of this construction, when the frame constituted by the gear wheel and the disk is rotated, the bracket of the arm 41 will move the upper end of the lever 59 to the right in Fig. 7, thus placing the spring 65 under tension. The degree of tension may be 65 nicely regulated by means of the extension 64, and the stem 67, or by means of the wing nut 57^a.

The yielding connection between the engine and the pump mechanism is the feature 70 that causes the economizer to operate properly. By means of this connection the relation between the pressure exerted by the pumps and that in the boiler may be so balanced that there is just sufficient excess power 75 in the pumps to cause the exhaust motive fluid to be returned to the source of supply.

It will be understood that by returning the exhaust products to the boiler while in a heated condition, a suitable saving in fuel 80 results.

I claim:

A device of the character specified, adapted to be arranged between a steam engine and the boiler from which the engine receives steam and adapted to be connected with the exhaust of the engine to return the exhaust products to the boiler, and comprising a pair of parallel cylinders, an operating shaft, a piston in each cylinder connected with the operating shaft, a driving shaft, a yieldable connection between the driving shaft and the operating shaft, a valve chest arranged between the cylinders, valves in connection with the chest and operated by the operating shaft, the chest and the cylinders being ported to alternately connect the ends of the cylinder to the boiler and to the exhaust.

JOHN LOUIS BARRETT.
